[57] CLAIM

The ornamental design for a handle for doors and windows, as shown and described.

DESCRIPTION

FIG. 1 is a top, front and side perspective view of a handle for doors and windows, showing our new design;

FIG. 2 is a front elevational view thereof;

FIG. 3 is a rear elevational view thereof;

FIG. 4 is a side elevational view thereof from the right of FIG. 2;

FIG. 5 is a side elevational view thereof from the left of FIG. 2;

FIG. 6 is a top plan view thereof;

FIG. 7 is a bottom plan view thereof;

FIGS. 8-14 are views similar to FIGS. 1-7, respectively, but showing a second embodiment thereof;

FIGS. 15-21 are views similar to FIGS. 1-7, respectively, but showing a third embodiment thereof;

FIGS. 22-28 are views similar to FIGS. 1-7, respectively, but showing a fourth embodiment thereof;

FIGS. 29-35 are views similar to FIGS. 1-7, respectively, but showing a fifth embodiment thereof; and,

FIGS. 36-42 are views similar to FIGS. 1-7, respectively, but showing a sixth embodiment thereof.
